Patent expires January 14, 1962

3 Claims. (Cl. 202—139)

1

At the present time coke ovens are constructed entirely of silica bricks. This construction suffers well known drawbacks resulting from the unfavorable expansion of the silica bricks.

Upon heating a coke oven battery which is constructed from silica brick, the brick expands in the direction of the length of the cells by about 15 to 20 centimeters. Moreover, owing to the temperature difference which prevails in a coke oven battery from the lower part to the upper part, this expansion is distributed irregularly along the surface. This almost always results in formation of fissures, more particularly in the regenerators of the coke oven.

Due to the stresses and strains involved in the irregular expansion of the silica brick in the heating walls and coking chambers of the coke oven battery, subject as they are to the temperature differentials involved in loading and the normal coking operation, the cooling of the coke oven battery has been beset with difficulties, particularly, for the purpose of shutting down to make the necessary repairs.

Silica brick is more expensive than ordinary silico-aluminous material, so that in the interest of economy, the lower parts of the oven, which are subjected to a temperature which ordinary brick withstands, are not fabricated of the silica brick.

The use of silica for the oven portions which are brought to a high temperature and more particularly of the piers offers unquestionable advantages based upon the improved pyrometric resistance of this material and also upon its higher resistance to the salts which are contained in the coal.

In view of these considerations, it has been proposed to build ovens the lower part of which is made of ordinary silico-aluminous products while the piers are made of silica.

These proposals are not satisfactory unless certain special precautions are observed.

Indeed, in ovens made in this manner the part which is brought to the highest temperature and made of silica expands much more than the lower part which is made of silico-aluminous products which often causes the formation of serious fissures.

To remedy this defect there have been proposed complicated devices comprising, more particularly, a kind of horizontal anchorage at the level of the middle part of the oven in order to compel the part made of silica to slide on the lower part when expanding.

This proposal is inadequate and unsatisfactory since the sliding of the silica can take place in an

2

irregular manner and especially because such ovens can be shutdown only with much difficulty owing to the disorder which is produced in their silica materials when the battery is cooled.

- 5 The oven made in accordance with the invention remedies all the above mentioned defects by eliminating the danger of fissures despite the expansion of the brick and silica brick by virtue of the arrangement of the horizontally elongated 10 coke oven chambers which discharge coke by horizontal pressure against one end of the coke mass in the chamber, the heating walls alongside the chamber and an intermediate portion of the battery structure being made of silica brick with a relatively high coefficient of thermal expansion, and the portions of the battery structure immediately above and below this intermediate portion being formed by a material having a relatively low coefficient of thermal expansion, each 15 of the heating walls being formed with a plurality of expansion joints arranged along the wall length in this intermediate portion, to divide the wall into blocks more narrow than high, and these blocks being provided with horizontal projections at the adjacent edges of adjacent blocks which overlap with each other, to take up the vertical shear stress in the expansion joints which is caused by the horizontal pressure against the coke mass in the adjacent coking chamber.

30 Coke ovens constructed in accordance with the invention are shown by way of example in the appended drawings, in which:

Figure 1 shows in the left portion a vertical sectional view and in the right portion an outer view of a pier of an oven constructed in accordance with the invention.

Figure 2 is a partial cross-sectional view of this oven.

Figures 3 and 4 are a horizontal sectional view 40 and a plan view of the pier of Fig. 1 respectively.

Figure 5 is a partial horizontal sectional view, on a larger scale than Figure 3, showing an example of the form of the joint between two blocks in the horizontal direction.

45 Figure 6 is a partial elevational view showing a modification of the form of two blocks in the vertical direction.

Figure 7 is a partial frontal vertical sectional view of a modification of execution in which the 50 blocks of the piers are extended up to the upper part of the oven.

Figure 8 is a cross-sectional view through line VIII—VIII of Figure 7.

Figures 9 and 10 are respectively an elevational 55 and an end view showing the assembly between

3

the bricks forming the successive blocks of a pier of the oven.

Figures 11 and 12 are two horizontal sectional views made in two successive layers in the upper part of the pier.

Figures 13 and 14 are two vertical sectional views shifted by 90° from each other of the inner position of the block guiding the circuit of the heating block.

Figure 15 is a horizontal sectional view through line XV—XV of Figure 14.

Each pier (Figures 1 to 4) is formed of separate and independent blocks made of silica bricks and each comprising at least one independent gas circuit formed of two flues 2, and 2' which are connected in their upper part by the horizontal passage 2a which completes the circuit in a "hair-pin" form as indicated through the arrow f1 (Figure 1).

Each one of these blocks can be secured in its position in the lower part 3 of the oven which is constructed of silico-aluminous material by means of a straight tenon 1a providing a partial embedding. The upper part 4 (Figure 1) is formed in one block of silico-aluminous material and the blocks 1 are connected thereto by tenons embedded in the same manner as for the lower part.

The expansion joints 5 are observable between the blocks 1 in a cold state. The width of said joints is adjusted on the basis of calculation in order that the joints close when the battery is heated; their width or separation in a cold state in the position of rest must be equal to the difference of expansion between the piers made of silica and the parts made of silico-aluminous material.

In practice, in order that one may be sure that these joints will close well, the separation is provided which is slightly lower than that which is indicated by the calculation.

At both ends, against the anchorages, the masonry of the oven lying outside the part of the oven which is carried to a higher temperature can be formed of blocks 6 of silico-aluminous materials.

In the upper part of these outer blocks 6 of silico-aluminous product, a horizontal joint can be provided to make allowance for the difference of expansion between said blocks and those which form the piers.

In order to avoid leakages between the blocks as well as for insuring their stability, one preferably provides the blocks 5, in the horizontal direction, in a form having broken joints with tenons and mortises, for example, such as shown in Figure 5.

In order to avoid undesirable stopping up of the spaces between the blocks during the building, cardboard or a material such as an asphalt which flows out later can be placed in said spaces. But it is preferable that these joints remain empty by placing therein, when the masonry is made, a removable board or metal sheet which is removed later.

Also the joint instead of being continuous in the vertical direction may be imbricated as shown in Figure 6.

The blocks 1 will generally be formed of silica bricks arranged in known manner for insuring the tightness of the masonry.

It is possible to modify the form of the joints and of the bricks to provide a connection so that said bricks remain perfectly contiguous when the battery is cooled or to provide a cement setting.

4

between the bricks to insure the perfect tightness of each of these blocks.

Instead of having one block of silico-aluminous material the upper part 4 of the oven can be formed of independent blocks of silico-aluminous material as an extension of the silica blocks of the piers.

In another form of execution the silica blocks of the piers are simply extended up to the upper part of the oven.

In both cases, in order to insure, in the upper part the closure of the coal compartments between the piers and the joints 5 one can adopt the arrangement shown in Figures 7 and 8 where the silica blocks are extended to the upper part of the oven. As may be seen from these figures, the inner faces of the oven, i. e. of each of said compartments are provided with two bossages 7, and 7' on which the bricks 8, 9, 10 rest and the linking sections being made either of silica or of silico-aluminous material so that they can be displaced independently by being laid on the said bossages. In order to insure the tightness of this closure the blocks 8 can be assembled together through tenons and mortises.

On the other hand, the upper parts of the piers of the oven are connected with one another through connections with broken joints 21 (Figure 7), said joints being made, with tenons and mortises, the tenon 22 of one of the blocks engaging a mortise provided between two tenons 23 of the other block.

One thus obtains a tight joint in the upper part of the pier which insures the tightness of the distillation chamber.

The mode of construction in accordance with the invention can be applied to a coke oven of any system, but it is particularly advantageous for those which comprise a so-called "hair-pin" circulation of the gases.

The fire-proof products used for the construction of the lower part and possibly of the upper part of the battery will normally be silico-aluminous products as are usually employed in the construction of coke ovens, but one can also use for this construction different products having a suitable expansion so that they better correspond to the application of the invention.

The advantages of the present system are obvious. The total expansion of the battery does not exceed that of the silico-aluminous parts which are brought to a comparatively reduced temperature.

The oven retains all of the advantages of a silica construction in all of the parts where the use of this product is desirable. One could, without inconvenience, extend the silica construction somewhat lower than indicated in the appended figures and provide a silica construction for the flues which bring the hot gases into the regenerator.

This construction provides improved tightness owing to the small expansion of the battery and because each block in which the circulation of the flue gases constitutes a perfectly tight system of small size.

Instead of grouping the vertical flues two by two in each block one could provide more of these, four by four for example, thus constituting two gas circuits in each block.

The tightness between the blocks in operation is insured. If a leakage should occur, it would take place between two cells and would have only a comparatively small effect; moreover, it is stopped rapidly through the production of carbon.

An economic advantage results from the battery construction using a quantity of silica brick which does not exceed 20 to 30% of the total weight of the fire-proof material.

The brick which constitute the piers of the oven come into contact with one another when the joints 8 yield under the effect of the expansion. If certain brick adhere together they tend to move apart from one another during cooling which tends to deform the pier.

This drawback is avoided in the oven made in accordance with the invention, through the arrangement of the brick constituting the pier of the oven (Figures 9 and 10). Each block 25 of one of the layers straddles both bricks 26¹, 26² of the lower layer and is assembled with both said bricks through a central tenon 27¹ of a height H and two side tenons 27², 27³ of a height h.

Likewise, the brick 25 straddles both bricks 28¹, 28² of the upper layer and is assembled with both said bricks through a central tenon 29¹ and two side tenons 29², 29³.

Thus, an assembly is obtained which opposes any untimely displacement of the brick:

(a) Either along f.10 perpendicularly to the plane of the pier.

(b) Or along f.11 in the plane of this pier.

The pier thus obtained withstands every external stress like a monolith.

The invention also covers another improvement to regulate the temperature, as much as possible, along the height of the oven.

For this purpose, in the upper part of the piers, the brick comprise, on the inner faces of the walls the outer face of which is in contact with the coal, one or more roughened portions to increase the surface for heat exchange by retaining the heat on the passage, to facilitate the transmission of the heat of the gas to the coal.

These roughened portions may vary on each face of each brick which forms the upper part of the block through their superposition, so as to divide the path of the gases along the walls of the flues in a zig-zag path which further promotes the exchange of heat.

Figures 11 and 12 show a form of execution of this arrangement. In these figures the roughened portions 45 are rounded and vary in number from one brick to another, for example, one brick may have one rough portion and those which lie immediately above and below may have two rough portions and so on, alternately. There can also be a variation of the number of rough portions in one and the same plane from one flue to another and from one face to the opposed face of the same flue, as shown in these figures.

It is possible to adjust the position of the horizontal passage 2a which unites the upper part of two coupled flues and completes each hair-pin circuit which is important for the heating of the coal contained in the upper part of the oven.

For this purpose (Figures 13 to 15) both inner faces of each block of the pier which are perpendicular to the intermediate partition 16 between both flues 22 of one and the same circuit, comprise, in the upper part, opposed grooves 17 provided between two projections 18 and adapted for receiving, in a variable number, a varying number of small bricks 19 the lowermost of which rests on the upper face of the partition to vary, at will, the total height of the latter and, concurrently, the position and the height of the horizontal channel 2a constituted by the free passage between the last small brick and the upper part of the flues.

The small bricks are advantageously provided

with holes 20 for their manipulation by means of hooks from the upper part of the oven.

Having thus disclosed the invention, what is claimed is:

- 5 1. A coke oven battery having horizontally elongated coke oven chambers arranged for the discharge of coke from each chamber by horizontal pressure against one end of the coke mass in the chamber and having heating walls alongside said chambers and having an intermediate portion of the battery structure, including the heating walls and coking chambers, made of silica bricks, having a relatively high coefficient of thermal expansion, and having the portions of the battery structure respectively above and below said intermediate portion formed of material having a relatively low coefficient of thermal expansion, each of said heating walls being formed with a plurality of vertical expansion joints in and confined to said intermediate portion of the battery structure and arranged at intervals along the length of the wall and dividing the latter into a plurality of blocks of substantially less horizontal than vertical extent, and having vertical heating flues in each block and having a vertical series of horizontally extending projections at each of the adjacent edges of adjacent blocks with the lateral projections at each of said edges overlapping the said projections at the adjacent edge of the adjacent block, whereby said overlapping projections are operative to take up the vertical shear stress in the expansion joints caused by the said horizontal pressure against the coke mass in an adjacent coking chamber.
- 10 2. A coke oven battery having horizontally elongated coke oven chambers arranged to discharge coke from each chamber by horizontal pressure against one end of the coke mass in the chamber, and having heating walls alongside said chamber together with an intermediate portion of the battery structure including the coking chambers made of silica brick having a relatively high coefficient of expansion, and having the portions of the battery structure above and below said intermediate portion formed of fire clay having a relatively low coefficient of thermal expansion, each of said heating walls being formed with a plurality of vertical expansion joints confined to said intermediate portion of the battery structure and arranged at intervals along the length of the wall to divide the wall into a plurality of blocks which are narrower than high, vertical bent flues in each of said blocks and a vertical series of horizontally extending projections at each of the adjacent edges of adjacent blocks, these horizontal projections overlapping at the adjacent edge of the adjacent blocks to take up vertical stress in the expansion joint.
- 15 3. A coke oven battery having horizontally elongated coke oven chambers arranged to discharge coke from each chamber by horizontal pressure against one end of the coke mass in the chamber, and having heating walls alongside said chamber together with an intermediate portion of the battery structure including the coking chambers made of silica brick having a relatively high coefficient of expansion, and having the portions of the battery structure above and below said intermediate portion formed of a material having a relatively low coefficient of thermal expansion, each of said heating walls being formed with a plurality of vertical expansion joints confined to said intermediate portion of the battery

structure and arranged at intervals along the length of the wall to divide the wall into a plurality of blocks which are narrower than high, a separate vertical bent flue in each of said blocks and a vertical series of horizontally extending projections at each of the adjacent edges of adjacent blocks, these horizontal projections overlapping at the adjacent edge of the adjacent blocks to take up vertical stress in the expansion joint, and said projections tending to separate 10 when the coke oven is cold.
